[57] CLAIM

The ornamental design for a vehicle dashboard, as shown and described.

DESCRIPTION

FIG. 1 is a perspective view of a vehicle dashboard showing our new design, the vehicle being shown in broken lines for illustrative purposes only and forms no part of the claimed design.

FIG. 2 is an enlarged top plan view thereof.

FIG. 3 is an enlarged front elevational view thereof.

FIG. 4 is an enlarged back elevational view thereof.

FIG. 5 is an enlarged bottom plan view thereof.

FIG. 6 is an enlarged left-hand end elevational view thereof.

FIG. 7 is an enlarged right-hand end elevational view thereof.
